CLAIM

The ornamental design for a safety syringe, as shown and described.

DESCRIPTION

FIG. 1 is a perspective view of a safety syringe with the cap attached, showing our new design;

FIG. 2 is a front side elevational view thereof, the rear side being a mirror image;

FIG. 3 is a left side elevational view thereof, the right side being a mirror image;

FIG. 4 is a top plan view thereof;

FIG. 5 is a bottom plan view thereof;

FIG. 6 is a perspective view thereof, with the cap removed;

FIG. 7 is a front side elevational view thereof, with the cap removed, the rear side being a mirror image;

FIG. 8 is a left side elevational view thereof, with the cap removed, the right side being a mirror image; and,

FIG. 9 is a bottom plan view thereof, with the cap removed.

FIGS. 1 through 9 depict a single embodiment of the ornamental design. FIGS. 1 through 5 depict the safety syringe with the cap attached. FIGS. 6 through 9 depict the same embodiment of the safety syringe shown in FIGS. 1 through 5, except that the cap has been removed, for ease of illustration. The broken line showing of parts of the drawings is included for the purpose of illustrating use and environment and forms no part of the claimed design.

1 Claim, 8 Drawing Sheets
